THREAD-WAXING DEVICE.

1,177,967.

Specification of Letters Patent.

Patented Apr. 4, 1916.

Application filed May 11, 1915. Serial No. 27,460.

To all whom it may concern:

Be it known that I, AUGUST R. SCHOENKY, a citizen of the United States, residing at Somerville, county of Middlesex, State of Massachusetts, have invented an Improvement in Thread-Waxing Devices, of which the following description, in connection with the accompanying drawing, is a specification, like characters on the drawing representing like parts.

This invention relates to thread-waxing devices such as are used in connection with wax-thread sewing machines for supplying wax to the thread.

One of the objects of the invention is to provide a novel thread-waxing device having provision for maintaining the portion of the wax mass through which the thread passes at a sufficient temperature to keep it in a proper state of fluidity without danger that the entire wax mass will become heated to such an extent as to boil over, and also to provide means whereby any excess heat that may be delivered to the wax mass through which the thread is drawn will be dissipated without effecting any overheating of the wax mass.

Another object of the invention is to provide a novel wax-containing receptacle which is removably sustained in a receiver or holder so that the receptacle can be readily removed from the holder whenever it is necessary to do so for cleaning it or repairing it.

Another object of the invention is to provide a thread-waxing device in which the thread extends transversely through the wax-containing receptacle and the latter is provided with means to prevent the escape of wax through the thread inlet passage and with novel means for stripping the wax from the thread as it is drawn through the delivery passage.

Other objects of my invention are to improve thread-waxing devices, all as will be more fully hereinafter set forth.

In order to give an understanding of my invention I have illustrated in the drawings a selected embodiment thereof which will now be described, after which the novel features will be pointed out in the appended claims.

In the drawings Figure 1 is an end view of a thread-waxing device embodying my invention; Fig. 2 is a side view of Fig. 1

with parts broken out to better illustrate the construction; Fig. 3 is a section on the line 3—3, Fig. 2.

The wax which is usually used for waxing thread in a wax thread sewing machine becomes solid or semi-solid at normal temperatures, and it is customary to heat the wax in order to render it sufficiently fluid to permit the thread to be drawn therethrough. It is necessary, however, to exercise considerable care in applying the heat to the wax because if the wax becomes too hot it deteriorates in quality and is likely to boil over, thus entailing extra work. In order to avoid these undesirable conditions I have provided herein a novel wax-containing receptacle and a novel manner of heating the receptacle by which the heat is applied to that portion only of the receptacle through which the thread passes whereby the portion of the wax mass through which the thread is drawn is kept at the proper temperature without danger that the entire body of the wax will become unduly heated. In fact with my invention it is not necessary to heat the entire wax mass, but only the particular portion of the wax through which the thread is drawn.

In the embodiment of the invention herein illustrated the wax is contained in a wax-holding receptacle 1 which is removably sustained in a holder or casing 2, the latter being constructed to present side walls, the latter having a box-like structure in which the receptacle 1 is received and being open at the top to permit the receptacle to be removed or placed in position. This top is closed by a cover 3 shown as hinged to the casing at 4, said cover constituting the cover for the receptacle 1. The wax-holding receptacle 1 is shown as having an outwardly-projecting flange 5 at its upper edge which overlies the top edge of the casing 2 and which assists to support the receptacle in the casing. When the cover 3 is closed it rests against the flange 5, as shown, and thus assists in holding the receptacle 1 in place. This wax-holding receptacle 1 is provided near its lower end with a thread inlet passage 6 and a thread outlet passage 7, said passages preferably being situated in alinement with each other so that the thread to be waxed may be drawn transversely through the receptacle, said thread

entering the inlet passage 6 and being discharged through the outlet passage 7.

The inlet passage 6 has associated therewith means to prevent the escape of the wax therethrough as the thread is entering the receptacle 1, and the outlet passage 7 has associated therewith a wax-stripping device for stripping the wax from the thread. The wax-stripping device is in the form of a compressible plug 8 having an aperture 9 through which the thread is drawn, means being provided to compress the plug more or less thereby to regulate the pressure thereof against the thread and thus determine the amount of wax to be left on the thread. This wax-stripping device is constructed so that the stripping plug 9 can be readily removed when it has deteriorated to such an extent as to make it necessary to replace it by a new plug. The construction herein provided for this purpose comprises a boss 10 extending from the wall of the receptacle 1, and into which is screw-threaded a sleeve 11 having a central opening in which the stripper 9 is received. Said sleeve 11 has screw-threaded into the end thereof a plug-compressing element 12 having a concave inner face 13 that engages the end of the plug, said plug-compressing element 12 being provided with a central aperture 14 through which the thread passes. Adjustment of the element 12 will compress the plug 9 more or less, thus regulating the size of the aperture through which the thread is drawn and consequently the wax-stripping effect of the plug. The sleeve 11 is readily removable from the boss 10 and when it has been thus removed the plug 9 can be forced from the sleeve by screwing up the element 12. A simple construction is thus provided for removably retaining the wax-stripping plug in position.

In the illustrated embodiment of my invention the boss 10 is formed as part of an element 15 which is rigidly secured to the wall of the receptacle 1.

The means associated with the inlet opening 6 to prevent the escape of wax therefrom is similar in construction to that employed for stripping the wax from the thread in that it comprises a compressible apertured plug 16 confined in a sleeve 17 that is screw-threaded in a boss 18 extending from the wall of the receptacle 1, said sleeve having screw-threaded thereinto a plug-adjusting element 19 having a thread-receiving aperture 20. The outer end of the thread-receiving aperture is flared, as shown at 21, to permit the thread to have easy entrance. By adjusting the element 19 the aperture in the compressible plug 16 can be so adjusted that it will fit the thread sufficiently tightly to prevent the escape of any wax through the passage 6. This construction has the advantage that the plug 16 can be readily removed

when it is necessary to replace it with a new plug.

The casing 2 is shown as having slots 200 in its opposite walls in which the bosses 18 and 10 are received, thus permitting the wax receptacle 1 to be removed from the casing whenever the cover 3 is opened.

It will be noted that the thread passages 6 and 7 are adjacent the lower end of the receptacle 1 and are situated in opposite sides of the receptacle so that the thread to be waxed is drawn transversely through the receptacle.

One feature of my invention relates to the manner in which the portion of the wax mass through which the thread is drawn is maintained in its fluid condition without necessitating the heating of the entire wax mass. I attain this object by making the lower end of the receptacle 1 in which the apertures 6 and 7 are formed comparatively narrow in one dimension and providing means for applying heat to said lower portion of the receptacle only. One convenient way of making the receptacle is to make it tapering so that it will have a pointed lower end 23, as shown in Figs. 1 and 3, the apertures 6 and 7 being formed in the pointed end. Means are provided for heating the lower pointed end of the receptacle 1, such means being herein illustrated as a heating element 24 having a groove or recess 25 formed in its upper face in which the lower pointed end of the receptacle 1 is received, as best seen in Fig. 3. This heating element 24 may be heated in any suitable way. I have herein shown it as provided with a steam chamber 26 having a general U-shape in cross section so as to partially embrace the lower pointed end 23 of the receptacle 1, said steam chamber being provided with an inlet pipe 28 and an outlet pipe 27 for the passage of steam to and from the steam space 26, said pipes being shown as extending through the slots 200. This heating element 24 is shown as secured to the bottom of the casing 2 by suitable screws 29, said element resting on leveling screws 30 by which it is properly leveled. With this construction the heat will be applied to that portion only of the receptacle 1 through which the thread passes and as the receptacle is pointed at its lower end there will be a comparatively small amount of wax in this heated portion of the receptacle. The heat which is developed from the heating element 24 will be sufficient to maintain the wax in the lower end of the receptacle in a melted condition, thus providing for properly waxing the thread as it is drawn through the receptacle, but the heat is insufficient to heat the entire wax mass in the receptacle 1 to a point that will tend to deteriorate it or would tend to make it boil over.

It will be noted that the wax-containing

receptacle 1 rests loosely on the heating element 24 and is, therefore, readily separable therefrom. The receptacle 1 can be readily removed from the casing 2 without disturbing the heating element.

5 The casing 2 may be provided with any suitable means for securing it to the machine with which the device is used. In the present embodiment of my invention said casing 10 has associated therewith an arm or bracket 31 by which the device is bolted or screwed to the machine with which it is used.

15 While I have herein illustrated the steam chamber 26 as having a U-shape in cross section, yet I desire to state that the shape and size of the steam space or chamber may be varied, depending on the pressure of steam which is used and the temperature which it is desired to develop.

20 An important feature of the present invention is the following novel principle involved therein. The combined means illustrated are such as to give a continuously-controlled mode of action whereby in effect 25 there are two different portions or masses of wax, namely, a comparatively small mass which is subject directly to the high heating influence and through which the advancing thread is drawn; and, secondly, a comparatively 30 much larger mass of wax which not only is not directly subject to the high heating influence but is subject to cooling influence, heat passing out of this part of the wax by conduction, convection and radiation. The particular construction illustrated is valuable for obtaining this condition of things by reason of the lower or heated portion of the receptacle being tapered or restricted in at least one direction 35 so as to give a small wax volume through 40 which the thread passes; whereas, the upper or enlarged or diverging portion of the receptacle contains the unheated and comparatively large wax mass referred to, gravity 45 serving to replace in the lower and highly heated portion of the receptacle the wax consumed by use, and the upper receptacle portion being thus available for continued new supplies of wax.

50 The described principle or mode of action, and the structure or means for securing the same, results in the preservation of a sort of balance as between the two different wax portions and the heat conditions, so that the 55 invention insures always a sufficient heating and melting of the wax at the point where the thread passes through it, while at the same time overheating, and injury to the wax is absolutely prevented. Thus, when 60 heat is supplied at a minimum rate through the heating device 24 or otherwise to the comparatively small wax mass through which the thread passes, the wax surrounding the thread is maintained in the proper 65 melted condition and at the proper tempera-

ture. There may be an extremely small amount of wax so maintained in the desired melted condition. The heating means, of course, must be adequate to make up for any losses of heat in this small wax mass, including the heat directly extracted by the waxed thread passing out of the receptacle. Preferably, the normal heat supply is somewhat more than necessary to maintain the described minimum heat conditions, and thus 70 there is insurance against insufficient heating of the wax portion through which the thread passes. Excessive supply of heat, or a continued supply of a high rate of heating without a proportionate heat subtraction, is 75 incapable of raising the temperature of the melted wax to an injurious degree. This is owing to the comparatively large mass of wax, which is not subject directly to the heating influence, but which on the contrary 80 is subject to the cooling influences mentioned. It is believed that the action in thus preserving the desired balance of temperature is somewhat as follows. The heating device 24 completely surrounds and 85 constantly acts upon the critical wax portion in the bottom of the restricted receptacle; such portion of wax, therefore, is always elevated to the desired degree of temperature. 90 An excess introduction of heat would in the first place have a tendency to elevate the temperature of the critical wax mass, but at once upon the commencement of this action the excess heat would be communicated upwardly to the larger wax mass. Such passage of excess heat into the larger mass 95 would take place to an extent dependent upon the excess of heat, so that dangerous overheating of the critical wax mass is avoided. A certain leeway of temperature 100 variation is permissible. The larger wax mass is capable of absorbing heat at a comparatively rapid rate without losing its function as a balance preserver, this being due to its capacity for distributing and constantly 105 throwing off its heat.

110 Generally speaking, the total result of the described action is that variations in heat supply or heat excess serve merely to cause variations in the volume or mass of properly melted wax at the bottom of the receptacle, and the apparatus is so designed that the extreme portion of the larger mass of wax need not ever become softened to the point of actually melting.

115 Another advantage resulting from my invention is that the heating of the wax is not accompanied by the evaporation of any of the desirable ingredients of the wax. Where the entire quantity of the wax in a 120 wax pot is melted and is kept hot, there will be a continual evaporation of the more volatile ingredients of the wax. This is prevented in my invention because the wax mass which is maintained at the highest 125 130

temperature and through which the tread passes is entirely sealed by the wax mass at the upper portion of the receptacle and which is of a much lower temperature. In fact, the wax mass at the top of the receptacle may not be melted at all, or at least it is maintained at so low a temperature that a deleterious evaporation does not take place. As a result all of the desirable ingredients of the wax are retained therein and a superior waxed thread can be produced.

While I have herein illustrated a selected embodiment of my invention, I do not wish to be limited to the constructional features shown.

I claim:

1. In a thread-waxing device, the combination with a wax-holding receptacle having a thread-receiving portion of relatively small volume and a wax-storage portion of relatively-large volume, said wax-receiving portion having provision for the thread to be waxed to pass therethrough, of means to apply heat to the thread-receiving portion only whereby the wax in the thread-receiving portion is maintained in a liquid state while the wax mass in the storage portion remains unmelted and exercises a cooling effect upon the heated wax in the thread-receiving portion.

2. In a thread-waxing device, the combination with a wax-holding receptacle having a thread-receiving portion of relatively small cross-sectional area and a wax-storage portion of relatively-large cross-sectional area, said wax-receiving portion having provision for the thread to be waxed to pass therethrough, of means to apply heat directly to the thread-receiving portion only whereby the wax in the thread-receiving portion is maintained in a liquid state while the wax mass in the storage portion remains unmelted and exercises a cooling effect upon the heated wax in the thread-receiving portion.

3. In a thread-waxing device, the combination with a holder or casing, of a wax-holding receptacle removably sustained by said holder and having in opposite walls alined inlet and outlet thread passages through which the thread to be waxed is drawn, of a wax stripper associated with the outlet passage, and means associated with the inlet passage to prevent the leakage of wax therethrough.

4. In a thread-waxing device, the combination with a box-like holding element, of a wax-holding receptacle removably sustained within said holding element and having in opposite walls thereof alined inlet and outlet thread passages through which the thread to be waxed is drawn.

5. In a thread-waxing device, the combination with a wax-holding receptacle hav-

ing a pointed lower end and provided in opposite walls adjacent said end with inlet and outlet passages through which the thread to be waxed is drawn, and means to apply heat to said pointed lower end only.

6. In a thread-waxing device, the combination with a wax-holding receptacle having a pointed lower end and provided in opposite walls adjacent said end with inlet and outlet passages through which the thread to be waxed is drawn, and a heating element on which said pointed lower end rests and which delivers heat directly to said end only.

7. In a thread-waxing device, the combination with a wax-holding receptacle having a thread-receiving portion of relatively small cross-sectional area and a wax-storage portion of relatively large cross-sectional area, said thread-receiving portion having provision for the thread to be waxed to pass therethrough, of means to apply heat to the thread-receiving portion only, said wax-storage portion having a capacity for holding a sufficient wax mass to absorb without becoming entirely melted any excessive heat from the wax in the thread-receiving portion over that necessary to maintain the wax in said thread-receiving portion in melted condition.

8. In a thread-waxing device, the combination with a wall of a wax-holding receptacle provided with a thread passage, of an internally-threaded boss on the exterior of said wall surrounding said passage, a sleeve screw-threaded into said boss and open at both ends, a compressible apertured plug removably confined in said sleeve, and a plug-compressing element screw-threaded to said sleeve for compressing the plug.

9. In a thread-waxing device, the combination with a wall of a wax-holding receptacle provided with a thread passage, of a sleeve removably secured to said wall, said sleeve being open at both ends, a compressible apertured plug situated in the inner end of said sleeve and removable from said end, and a plug-compressing element carried by said sleeve at its outer end and by which the plug can be compressed more or less.

10. In a thread-waxing device, the combination with a wax-holding receptacle having a pointed lower end provided with inlet and outlet passages for the thread to be waxed, of a heating element having in its upper face a groove or recess to receive the lower pointed end of the receptacle whereby the heat will be applied to that portion of the receptacle only through which the thread passes.

11. In a thread-waxing device, the combination with a holder or casing, of a heating element within the casing, and a wax-holding receptacle removably received within the casing and resting on the heating element, said receptacle having provision

for the thread to be waxed to pass therethrough.

12. In a thread-waxing device, the combination with a holder or casing, of a heating element within the casing, and a wax-holding receptacle removably received within the casing and resting on the heating element, said receptacle having in opposite walls thereof a thread inlet passage and a thread outlet passage.

13. In a thread-waxing device, the combination with a box-like casing having slots formed in two opposite walls thereof, of a wax-holding receptacle removably received within said casing and provided with a thread inlet and a thread outlet passage in opposite walls thereof in alinement with said slots whereby the receptacle can be removed from the casing without removing the thread therefrom.

14. In a thread-waxing device, the combination with a wax-holding receptacle having in one wall an outlet aperture through which the thread is drawn and an internally screw-threaded boss on the exterior of said wall surrounding said aperture, an open-ended sleeve screw-threaded into said boss, a compressible perforated wax-stripping plug within said sleeve, a plug-compressing element screw-threaded into said sleeve and engaging said plug, and a casing in which said receptacle is removably received and which is provided in opposite walls with slots through which the bosses extend.

15. In a thread-waxing device, the combination with a wax-holding receptacle having in one wall thereof a passage through which the thread is drawn, of an open-ended sleeve removably secured to said wall, a compressible apertured plug within said sleeve and adapted to be placed in position through or ejected from the open end of the sleeve, and a plug-compressing element screw-threaded to the opposite end of the sleeve and by which the plug may be compressed when the

sleeve is in its operative position or said plug may be ejected when the sleeve is removed.

16. In a thread-waxing apparatus, a wax holder, means for constantly supplying high heat directly to a comparatively small mass of the wax in said holder, and means for permitting the passage of thread through such comparatively small mass of directly-heated wax; said holder constructed to maintain such small heated wax mass and in communication therewith a comparatively large heat-balancing wax mass not subject to direct heating but adapted to take up and dissipate any heat excess in the said smaller wax mass.

17. In a thread-waxing device, the combination with a wax-holding receptacle having provision for the thread to be waxed to pass through one portion only thereof, of means exterior to said receptacle to heat said portion only.

18. In a thread-waxing device, the combination with a wax-holding receptacle having provision for the thread to be waxed to pass transversely therethrough at its lower end, of means exterior to said receptacle to apply heat to said lower end only.

19. In a thread-waxing device, the combination with a wax-holding receptacle shaped to present at its lower end a comparatively small cross-sectional area and at its upper end a much greater cross-sectional area, said receptacle having provision for permitting the thread to be waxed to pass through the lower end of the smaller cross-sectional area, and means to apply heat to said lower end only whereby the wax mass in the larger upper portion of the receptacle is not subjected to the action of the heating means and exercises a cooling effect upon the heated wax at the lower end of the receptacle.

In testimony whereof, I have signed my name to this specification.

AUGUST R. SCHOENKY.
